UNITED STATES PATENT OFFICE.

HENRY C. RASNER, OF SAN FRANCISCO, CALIFORNIA.

WISE.

SPECIFICATION forming part of Letters Patent No. 473,343, dated April 19, 1892.

Application filed January 27, 1890. Serial No. 338,274. (No model.)

To all whom it may concern:

Be it known that I, HENRY C. RASNER, a citizen of the United States, residing in the city and county of San Francisco, State of California, have invented an Improvement in Vises; and I hereby declare the following to be a full, clear, and exact description of the same.

My invention relates to that class of vises in which a segmental or mutilated screw engages a corresponding nut, whereby when the screw is turned to one position it is free of the nut, and the movable jaw of the vise may be rapidly moved in or out to approximate position, and when the screw is turned in another position it will engage the nut, and will thereby tighten up the movable jaw on the work.

The object of my invention is to provide a simple form and construction of this class of vises, the general advantage of which is well known—namely, the capacity of being rapidly set to approximate position and then tightened on the work instead of being slowly set up, as by the ordinary power-screw.

My invention consists in the novel constructions and combinations hereinafter fully described, and specifically pointed out in the claim.

Referring to the accompanying drawings for a more complete explanation of my invention, Figure 1 is a vertical longitudinal section of the jaws of my vise, the screw being in elevation. Fig. 2 is a bottom view of my vise. Fig. 3 is a cross-section through nut B and sockets C. Fig. 4 is a longitudinal section of nut B and elevation of screw F to show the bevels of the thread ends.

A is a plate, which forms the fixed jaws of the vise and may be secured in any suitable manner to a bench or block, as may be desired. To the lower end of this plate is firmly secured a nut B, which is internally threaded, its threads, however, being only partial—that is to say, it is a segmental or mutilated nut, its threads not extending all the way around but being only in one portion. (Here shown as the upper portion.)

C are suitable rod-guides on each side of the nut, and preferably cast or formed with the fixed jaw.

D is the movable jaw of the vise. Secured to and extending from this jaw are the guide-

rods E, which pass through the rod-guides C, whereby the jaw is supported and guided.

F is the operating-screw of the vise. The outer end of this screw passes through the movable jaw D, and is so seated therein as to rotate freely, not, however, being threaded in it or in any nut carried by it, as is customary, but freely journaled in it, being held therein by flanges or collars on each side. The head of the screw is provided with the usual hand-lever G, and its rotation is limited and defined by a small lug f on the screw-head, which is adapted to come in contact with a fixed stop-lug d on the movable jaw.

The screw F is not a perfect one, but its threads, as shown, are only partial—that is to say, do not extend wholly around the screw. The screw is therefore a segmental or mutilated one, having threads on one side and a smooth portion on the other side. The screw passes through the nut B, as shown.

The operation of the device is as follows: When it is desired to rapidly move the sliding jaw to or from the fixed jaw to approximate position, the screw is so turned as to carry its threads out of engagement with the threads of the nut, bringing its smooth portion opposite said threads, this portion being defined by the contact of the lug f with the stop d. In this position the screw is entirely free of the nut, and the sliding jaw may be rapidly and easily moved to approximate position to receive the work and to bear upon it. Now to tighten the movable jaw on the work, the screw is turned back again so that its threads engage the nut, and as the engagement takes place the screw is fed forwardly, thereby tightening the jaw on the work. There is one difficulty to be encountered and overcome in this form of construction—namely, the avoidance of an abutting contact between the ends of the threads on the screw and the ends of the threads in the nut when the screw is turned to its engagement. It will readily be seen that when the movable jaw is moved to approximate position it may so happen that the ends of the two threads may be directly opposite each other, and will come into positive contact and prevent the screw from engaging the nut. Now to avoid this I bevel or incline the end of each thread on the screw, as shown at x, on its inner side, and I

correspondingly bevel the adjacent end of the 5 thread of the nut, as shown at x' . Now the effect of this is that when the screw is turned to its engagement with the nut, these two bevels, engaging each other, throw the screw outwardly or backwardly onto the next thread of the nut before the engagement becomes perfect and the tightening takes place. If the bevels were on the other sides of the 10 threads, the tightening would take place immediately, and the movable jaw would be set up on the work before the full engagement of the threads took place; but by putting the bevels on the side I have shown the screw is 15 thrown backwardly onto the next thread, so that it has room to tighten or close in again upon the full engagement of the threads.

I am aware that in vises of this class segmental or mutilated screws have engaged 20 corresponding nuts, whereby the movable jaw might be rapidly slid in and out to approximate position; but in such cases it is common to effect the tightening by threading

the screw in the movable jaw or in the nut carried thereby. I do not therefore claim, 25 broadly, the engagement of a segmental screw with a corresponding nut; but

What I do claim as new, and desire to secure by Letters Patent, is—

In a vise, the combination of a fixed jaw, a 30 movable jaw, a nut in the fixed jaw having a mutilated thread, an operating-screw carried by the movable jaw, having, also, a mutilated thread, the ends of both the threads on the nut and the operating-screw being beveled 35 from front to rear, so that when the lines of the threads on the screw and nut come in alignment the operating-screw will be thrown backward one thread, substantially as and for the purpose set forth.

In witness whereof I have hereunto set my hand.

HENRY C. RASNER.
